DESIGN FOR A COMBINED SEAT AND TELEPHONE COMPARTMENT

Greta Hale, Chicago, Ill.

Application June 22, 1936, Serial No. 63,433

Term of patent 7 years

To all whom it may concern:

Be it known that I, Greta Hale, a citizen of the United States, residing at Chicago, in the county of Cook and State of Illinois, have invented a new, original, and ornamental Design for a Combined Seat and Telephone Compartment, of which the following is a specification, reference being had to the accompanying drawing, forming a part thereof.

bined seat and telephone compartment, showing my design with the telephone compartment in closed position; and

Figure 2 is a rear perspective view thereof, with the telephone compartment in open position.

I claim:

The ornamental design for a combined seat and telephone compartment, as shown.

GRETA HALE.
